Primary Examiner — Ricky Pham(74) *Attorney, Agent, or Firm* — Baker Hostetler LLP(57) **CLAIM**

The ornamental design for an electric mixer, as shown and described.

DESCRIPTION

FIG. 1 is a top, rear, and left side perspective view of an electric mixer;

FIG. 2 is a front view of the electric mixer;

FIG. 3 is a rear view of the electric mixer;

FIG. 4 is a left side view of the electric mixer;

FIG. 5 is a right side view of the electric mixer;

FIG. 6 is a top view of the electric mixer;

FIG. 7 is a bottom view of the electric mixer;

FIG. 8 is a bottom, front, and left side perspective view of the electric mixer; and,

FIG. 9 is an enlarged perspective view of a portion of the electric mixer.

The broken lines shown in the drawings of an electric mixer are for illustrative purposes only and form no part of the claimed design.
